AQUARIUM AIR PUMP

Monte L. Levin, New York, N.Y., assignor to Aquariums Incorporated, Maywood, N.J., a corporation of Delaware

Filed Apr. 10, 1968, Ser. No. 11,394

Term of patent 14 years

Int. Cl. D15—02

U.S. Cl. D65—1

FIG. 1

FIG. 2

FIG. 3

FIG. 4

FIGURE 1 is a perspective view of an aquarium air pump showing my new design;

FIGURE 2 is a side elevational view thereof;

FIGURE 3 is a front view thereof; and

FIGURE 4 is a bottom view thereof.

The electric cord is shown in broken lines in FIGS. 1, 2 and 4 for illustrative purposes only.

I claim:

The ornamental design for an aquarium air pump, substantially as shown and described.
